MULTI-PURPOSE CLAMP FOR HOLDING WITHIN
ITS TUBULAR ELEMENTS PENCILS, WIRES OR
SIMILAR ARTICLES

James J. A. Sartore, 128 Morris St., Albany, N.Y. 12208

Filed Dec. 5, 1972, Ser. No. 312,376

Term of patent 14 years

Int. Cl. D8—08

U.S. Cl. D8—259

FIG.
1

FIG.
2

FIG.
3

FIG.
4

FIG. 1 is a left end elevational view of a multi-purpose clamp for holding within its tubular elements pencils, wires or similar articles as seen from the left of FIG. 1;

FIG. 2 is a side elevation thereof;

FIG. 3 is a right end elevational view;

FIG. 4 is a perspective view of one of the elements.

The broken lines are for illustrative purposes only.

I claim:

The ornamental design for a multi-purpose clamp for holding within its tubular elements pencils, wires or similar articles, substantially as shown and described.
